CONTAINER FOR FLOWABLE MATERIALS OR THE LIKE

Robert T. Johnson and Gaylor W. Brown, Beaverton,
Mich., assignors to Koehring Company

Filed Sept. 21, 1970, Ser. No. 25,092

Term of patent 14 years

Int. Cl. D9—01

U.S. Cl. D9—169

FIG. 1 is a partially broken away elevational view of a container for flowable materials or the like showing our new design;

FIG. 2 is a top plan view, it being understood that the grooves shown extend completely around the container in the path indicated by the dotted lines;

FIG. 3 is a bottom plan view; and

FIG. 4 is a perspective view thereof.

We claim:

The ornamental design for a container for flowable materials or the like, as shown and described.
